(57) **CLAIM**

I claim the ornamental design for a hand held gun-style cleaning tool, substantially as shown.

DESCRIPTION

FIG. 1 is a first perspective view of the hand held gun-style cleaning tool of the present invention.

FIG. 2 is a second perspective view of the tool.

FIG. 3 is a side elevation view of the tool, with the opposite side having the same appearance.

FIG. 4 is a top elevation view of the tool.

FIG. 5 is a bottom elevation view of the tool.

FIG. 6 is a front elevation view of the tool; and,

FIG. 7 is a rear elevation view of the tool.
